[57] CLAIM

The ornamental design for a fragmentary box wall structure, as shown and described.

DESCRIPTION

FIG. 1 is a top and front perspective view of a fragmentary box wall structure showing our new design:

FIG. 2 is a side elevation view of the fragmentary box wall structure of FIG. 1, the other side view being a mirror image;

FIG. 3 is a front elevational view of the fragmentary box wall structure of FIG. 1;

FIG. 4 is a rear elevational view of the fragmentary box wall structure of FIG. 1;

FIG. 5 is a top plan view of the fragmentary box wall structure of FIG. 1; and,

FIG. 6 is a bottom plan view of the fragmentary box wall structure of FIG. 1.

The broken line showing of the box floor and lid panels are environmental only and form no part of the claimed design.
